PAPER ROLL HOLDER

Francis T. Smith, Bridgeport, Conn.

Application September 1, 1939, Serial No. 292,985

5 Claims. (Cl. 242—55.2)

This invention relates to holders for rolls of toilet paper, towels, and the like, and has for one of its objects the provision of an extremely simple device which not only permits the rolls to be rapidly and easily inserted, but also permits the roll-holding yoke to be easily and quickly removed from a supporting base without in any way springing or distorting any of the parts of the yoke or base.

One of the features of this invention is the provision of an extremely simple roll-holding yoke which is made from a single piece of wire, all parts of which lie in one plane, and which is open at one end so that the paper roll may be slid onto the yoke and the empty core removed without springing the yoke.

Another feature of this invention is the provision of a simple supporting base for the roll-holding yoke which may be fastened to the wall by wood screws or otherwise, and which is adapted to receive the roll-holding yoke and hold it in place against casual displacement without the necessity of springing the yoke or any parts of the base. Accordingly, the base may be made of rigid material such as Bakelite or porcelain, and of various colors so as to match the other fixtures with which it is used. If desired, the base may also be formed as a sheet metal stamping.

Other features and advantages will herein-after appear.

In the accompanying drawing which illustrates several forms of my invention—

Figure 1 is a perspective view, showing the roll holder of the present invention supporting a roll of paper.

Fig. 2 is a side elevation of the device shown in Fig. 1.

Fig. 3 is a front view of a modified form of the invention, wherein the base is made of a metal stamping.

Fig. 4 is a side view of the parts shown in Fig. 3.

As shown in the accompanying drawing, the device of this invention comprises two simple parts—a base 10 and a roll-supporting yoke 11.

According to the present invention, the yoke 11 is made approximately U-shape, with the leg 12 of the U constituting a shaft on which the yoke is mounted, and the leg 13 of the U constituting a support for a roll of paper 14, the legs 12 and 13 of the U being connected by a portion 15. Opposite the portion 15, the yoke is left open so that the roll of paper 14 may be slid endwise over the rod 13 to the position shown in Fig. 1, in which the roll of paper is supported for

rotation. The portion 15 of the U-shaped yoke prevents endwise movement of the roll to the right as shown in Fig. 1, and, to prevent endwise movement of the roll to the left, the rod 13 is provided with an upwardly bent arm 16 which engages the side of the roll or of the core 17 on which the roll is wound. The length of the arm 16 is such that it will pass through the opening 18 of the core 17 when the roll is slid onto the rod 13. The weight of the roll of paper keeps the roll from raising to the position where the arm 16 would pass through the opening 18 of the roll.

The base 10 which supports the yoke 11 is a very simple part. As shown in Fig. 1, it may be made by molding porcelain, Bakelite or the like. As shown, it has a flat plate-like portion 22, the rear surface of which is adapted to be affixed to a wall, and, at opposite ends, has projections 20 provided with upwardly projecting ears 21 which are spaced from the front surface 19 of the plate 22. Midway between the projections 20 there is a lug 23. The shaft 12 of the yoke is received between the ears 21 and the plate 22 and supported on the upper surface of the projections 20. The lug 23 is so located as to engage the upper portion of the shaft 12 when the shaft is in position—the projections 20, ears 21, and lug 23 holding the shaft 12 in position on the base 10 and permitting swinging movement of the yoke and the paper roll supported thereby. Longitudinal movement of the shaft 12 is prevented on the one hand by the portion 15 of the yoke engaging the ear 21 at the right-hand side of the plate 22, and on the other hand by a bent portion 24 on the shaft 12 engaging the left-hand ear 21.

This portion 24 is bent so as to lie in the same plane as the other parts of the yoke 11, thereby permitting the formation of the yoke on a wire bending machine with very simple tools.

The base 10 may be secured to a supporting structure, such as a wall, by screws which pass through countersunk holes 25 extending through the plate 22. These countersunk holes preferably are placed directly behind the shaft 12 so as to be substantially concealed by the shaft.

When installing the roll holder, assuming that the yoke 11 has been removed from the base 10, the base 10 is secured to the wall by screws passing through the holes 25. Then the yoke, without bending any part of the same, may be slid into position on the base 10. This may be done by holding the yoke at right angles to the wall, sliding the right-hand end of the shaft 12 down-

wardly between the right-hand ear 21 and the plate 22, sliding the shaft to the left while the bent portion 24 extends forwardly so that it will pass under the lug 23 and until the bent portion 24 strikes the left-hand ear 21, then swinging the yoke vertically so as to be substantially parallel with the wall, and then continuing the movement of the shaft to the left until the bent portion 24 has passed the left-hand ear 21, whereupon the yoke is permitted to swing downwardly so that the bent portion 24 is confined against lateral movement to the right by the ear 21 and the projection 20. The paper roll is then slid over the rod 13 of the yoke to the position shown in Fig. 1.

When the roll is in this position, even should the yoke be swung upwardly, the side of the roll of paper would strike the wall on which the device is mounted before the bent portion 24 assumes the vertical position which it must assume in order to pass the left-hand ear 21, and thus the yoke is held on the base 10 against accidental or casual removal so long as the roll of paper is supported by the yoke.

The yoke 11 is made of stiff wire of such diameter that the yoke is substantially rigid and will support the roll of paper without appreciable bending, even though the rod 13 and shaft 12 are only connected at one side as by the portion 15.

As shown in Figs. 3 and 4, the base may be made of a sheet metal stamping. In this case, the sheet metal plate 22a has upwardly and forwardly bent ears 21a at each side, and between the ears 21a a horizontally extending ear 23a performing the functions of the projections 20 with their ears 21 and the lug 23. The plate has holes 25a by means of which it may be secured to a supporting structure such as a wall.

In Fig. 3, the holes 25a are not directly behind the shaft 12, and this arrangement may also be employed in connection with Fig. 1 if desired.

Variations and modifications may be made within the scope of this invention and portions of the improvements may be used without others.

I claim:

1. A paper roll holder having a substantially U-shaped yoke disposed with its parallel legs horizontal, one of said legs constituting a rod for receiving the core of a roll of paper, and the other of said legs constituting a shaft on which said rod and paper roll is swung, and a wall supported base for said rod, said base having a pair of ears extending outwardly from the exposed face of said base and then upwardly parallel to said face to slidably receive and support the shaft; and a lug between said ears to prevent vertical movement of the shaft.

2. A paper roll holder having a substantially U-shaped yoke disposed with its parallel legs horizontal, one of said legs constituting a rod for receiving the core of a roll of paper, the other of said legs constituting a shaft on which said rod and paper roll is swung, and a wall supported base for said rod, said base having a pair of ears extending outwardly from the exposed face of said base and then upwardly parallel to said face to slidably receive and support the shaft; and a lug between said ears to prevent vertical move-

ment of the shaft, the shaft having a bent arm at one end to engage the adjacent ear and prevent longitudinal movement of the shaft, and being placed in position on the base by sliding the same longitudinally along the base and rotating the shaft without extending the yoke behind the wall-engaging face of said base to permit said arm on the shaft to pass by a supporting ear and the lug to bring the shaft to a position wherein it is supported by both of said ears with the arm engaging its adjacent ear.

3. A paper roll holder having a substantially U-shaped yoke, one leg of which is adapted to support a roll of paper, a wall supported rigid base adapted to engage and support the other leg of the yoke; a pair of ears extending outwardly from the exposed face of said base and then upwardly parallel to said base adapted to slidably receive said leg of the yoke without extending the yoke behind the wall-engaging face of the base and mount the yoke for pivotal movement; and a lug disposed between said ears and adapted to hold the said leg of the yoke in operative position on the ears against casual vertical movement, the extremities of both legs being bent toward each other to form restraining lugs, the lug of the roll supporting leg preventing movement of the roll longitudinally of the leg, and the lug of the supported leg holding the leg against movement laterally of the base.

4. In a device of the type described, a mounting plate adapted to be securely fastened to a wall; a pair of upstanding ears carried by the exposed face of said plate, each forming at opposite sides of the plate a groove open at the top; a lug disposed intermediate said ears and presenting a downwardly facing shoulder; and a rod having two parallel and separated sections, one of said sections serving to receive a paper roll, the extremity of this section being bent toward the other section to prevent movement of the roll longitudinally of the section, the other of said sections being slidably received in the grooves formed by said ears and held against movement upwardly of the grooves by the downwardly facing shoulder of said lug.

5. In a device of the type described, a mounting plate adapted to be securely fastened to a wall; a pair of upstanding ears carried by the exposed face of said plate, each forming at opposite sides of the plate a groove open at the top; a lug disposed intermediate said ears and presenting a downwardly facing shoulder; and a rod having two parallel and separated sections, one of said sections serving to receive a paper roll, the extremity of this section being bent toward the other section to prevent movement of the roll longitudinally of the section, the other of said sections being slidably received in the grooves formed by said ears and held against movement upwardly of the grooves by the downwardly facing shoulder of said lug, the extremity of the last-named section being bent toward the other section to form a laterally extending lug adapted to engage one of said ears when the section is supported by said ears to prevent movement of the section laterally of the plate.
